UNITED STATES PATENT OFFICE

125,131

DESIGN FOR A TOBACCO PIPE CLEANING TOOL

Arthur A. Giesen, Chicago, Ill.

Application April 20, 1940, Serial No. 91,825

Term of patent 3½ years

To all whom it may concern:

Be it known that I, Arthur A. Giesen, a citizen of the United States, residing at Chicago, in the county of Cook and State of Illinois, have invented a new, original, and ornamental Design for a Tobacco Pipe Cleaning Tool, of which the following is a specification, reference being had to the accompanying drawing, forming a part thereof.

Figure 1 is a side elevation of a tobacco pipe cleaning tool showing my new design;

Figure 2 is a top plan view thereof;

Figure 3 is an end elevation.

I claim:

The ornamental design for a tobacco pipe cleaning tool, substantially as shown.

ARTHUR A. GIESEN.
